AUTOMATIC CIRCUIT BREAKER

Filed April 6, 1929

Inventor: Joseph Sacks
Attorney: S. Jay Teller

UNITED STATES PATENT OFFICE

JOSEPH SACHS, OF WEST HARTFORD, CONNECTICUT

AUTOMATIC CIRCUIT BREAKER

Application filed April 6, 1929. Serial No. 353,052.

This invention relates particularly to circuit breakers of the type disclosed in my co-pending applications for automatic circuit breakers Ser. No. 271,819, filed April 21, 1928, 5 Ser. No. 283,060, filed June 5, 1928 and Ser. No. 332,924, filed January 16, 1929. In a circuit breaker of this type the electro-responsive means, which may be a thermostatic element such as an electro-thermal bi-metallic strip, is so mounted as to be bodily movable in whole or in part with the movable contact member of the circuit breaker.

In each of the before mentioned applications, the construction is such that the electro-responsive device, as for instance the electro-thermal strip, serves in and of itself as a releasable latch, which normally holds the contact member in its closed circuit position and which normally serves as a means whereby the contact member may be operated by the actuator for ordinary switching purposes. The construction referred to has the advantage of great simplicity and is for this reason ordinarily preferable. However, for some classes of service it may be desirable to avoid the use of the electro-responsive element as a mechanical connector while retaining the advantage resulting from the mounting of the said element for bodily movement.

The principal object of the present invention is to provide a construction of the type referred to having means mechanically operative entirely independently of the electro-responsive element for normally holding and operating the contact member, the said means, however, being so constructed and so related with the electro-responsive element as to be automatically released to permit movement of the contact member upon the actuation of the said element by reason of the attainment of abnormal current conditions, such as passage of excess current.

Other objects of the invention will be apparent from the following specification and claims.

As concerns the broader phases of the invention there can be wide variation as to some of the details of construction, particularly as concerns the details of the main body

and of the movable contact member. I prefer and have shown in the drawings a construction which as to these details is similar to the construction shown in my aforesaid co-pending application, Ser. No. 283,060. It will be understood that the drawings are intended for illustrative purposes only and are not to be construed as defining or limiting the scope of the invention, the claims forming a part of this specification being relied upon for that purpose.

Of the drawings:

Fig. 1 is a front view of a circuit breaker embodying the invention, the enclosing cover being shown in section.

Fig. 2 is a side view of the parts shown in Fig. 1, the cover and the base being shown in section along the line 2—2 of Fig. 1.

Fig. 3 is a transverse sectional view taken looking upward along the line 3—3 of Fig. 2.

Fig. 4 is a vertical sectional view taken along the line 4—4 of Fig. 2.

Fig. 5 is a detailed perspective view of the electro-thermal strip.

Fig. 6 is a fragmentary vertical sectional view taken along the line 6—6 of Fig. 1 and showing the parts in the same relative positions as in Fig. 2.

Figs. 7 and 8 are vertical sectional views similar to Fig. 6, the several parts being in different relative positions and being more fully shown.

Referring to the drawings, it will be observed that the main body of the circuit breaker unit comprises two spaced insulating side plates 1, 1 and metallic cross members 2 and 3 connected at their ends with the side plates by means of nuts 4, 4. The said body of the circuit breaker unit is connected with a base 5 by means of nuts or screws 6, 6 which extend through holes in the members 2 and 3 and hold them in contact with metal plates 7 and 8 carried by the base. The said metal plates 7 and 8 are provided with screws 7^a and 8^a constituting wire connecting terminals.

I provide a contact member which is movably mounted with respect to the body, preferably being mounted for pivotal movement. As illustrated the contact member includes two side plates 9, 9 which are pivotally mount-

ed upon transverse studs 10, 10 carried by the side plates 1, 1 of the body and projecting inward therefrom. The studs 10, 10 have integral heads 11, 11 at their inner ends, and the side plates 9, 9 are spaced from the side plates 1, 1 by means of bushings 12, 12 surrounding the studs 10, 10. The two side plates 9, 9 are held in proper spaced relationship by means of spacing rods 13, 13, which are connected with the side plates by means of screws 14, 14.

Suitable electric contacts are provided, there preferably being two stationary contacts carried by the body of the circuit breaker and two movable contacts carried by the contact member and adapted to be engaged with and disengaged from the respective stationary contacts. The details of the contacts may be widely varied but as illustrated the two stationary contacts 15, 15 are carried respectively by the two side plates 1, 1. Each of the contacts 15 is formed as a part of a flat strip 15^a bent as shown in Fig. 2 and having the contact face thereof located in a transverse plane. As shown most clearly in Figs. 2 and 3 each side plate 1 is provided with an opening 16, and the corresponding contact is located immediately adjacent the opening and at the inner side of the plate. Each contact strip 15^a is provided with an ear 17, in a vertical plane at the outer side of the plate and held in engagement therewith by means of a bolt 18. The right hand contact 15 is electrically connected with the lower transverse member 2 by means of a strap 19 held in place at its upper end by a nut on the corresponding bolt 18 and at its lower end by the corresponding nut 4. The left hand contact 15 is electrically connected with the upper transverse member 3 by means of a strap 20 held in place at its lower end by a nut on the corresponding bolt 18 and at its upper end by the corresponding nut 4.

The movable electrical contacts are shown at 21, 21, these contacts projecting laterally from the side plates 9, 9 of the contact member and being adapted to engage the stationary contacts 15, 15 as shown in Fig. 2. Extending transversely between the two side plates 9, 9 is an insulating bar 22 and the two contacts 21, 21 are extended inward as shown at 21^a, 21^a through suitable apertures in the side plates so as to engage the bar 22 at the lower face thereof as shown in Figs. 3, 7 and 8. The said contacts 21, 21 are held in place by means of screws 23, 23 extending through the bar 22.

The details of construction and mounting the fixed and movable contacts are not herein claimed, being set forth and claimed in my copending applications for automatic circuit breakers, Serial No. 283,060 filed June 5, 1928 and Serial No. 365,419 filed May 23, 1929.

The entire contact member is biased for movement in the counter-clockwise direction

toward its upper open-circuit position, and for this purpose I have provided coil springs 24, 24 surrounding the bushings 12, 12 and having their ends connected respectively with the body and the contact member.

I provide a movable member which I will term an actuator, this member serving as the means for moving or actuating the contact member for normal switching purposes or to effect closing of the circuit after automatic opening thereof. When the contact member is pivotally mounted as shown and described, the actuator is preferably also pivotally movably mounted for movement about an axis parallel with the contact member axis. As shown the actuator is in the form of a member 25 pivotally mounted on a rod 26 extending transversely between the side plates 1, 1. The member 25 is held against transverse movement by means of bushings 27, 27 on the rod 26.

The member or actuator 25 is provided with a projection 28 constituting a handle whereby it may be moved manually. The actuator has an arcuate slot 30 therethrough and a rod 31 carried by the side plates 1, 1 extends through the slot. The rod by reason of its engagement with the ends of the slot serves as a means for limiting the movement of the actuator. The actuator is biased toward its open-circuit position, that is toward its lower position, by means of a coil spring 32 surrounding one of the bushings 27, 27 the spring having its ends connected respectively with the corresponding side plates 1 and with the actuator.

I provide an electro-responsively controlled toggle link means between the actuator and the contact member which connection is operative to enable the actuator to operate the contact member for ordinary switching purposes and which is automatically released in so far as its holding function is concerned upon the attainment of abnormal current conditions in the circuit, so as to permit the contact member to automatically move independently of the actuator to its open-circuit position. The electro-responsively controlled means may be widely varied in construction but it is essential that at least a portion of the said means be mounted for bodily movement with the contact member, or with the actuator, or with both.

I prefer and have shown as a part of the electro-responsively controlled means a thermally responsive element which preferably is a current carrying thermostatic bimetallic strip. The said strip is adapted to be deflected by reason of the heating action of excess current therein in accordance with the well known action of such bi-metallic strips. The bi-metallic strip is shown in the drawing at 33, this strip being substantially U-shaped and having the legs of the U connected respectively with the movable con-

tacts 21, 21. As illustrated the end portions of the said legs are provided with holes through which extend the aforesaid screws 23, 23 nuts 34, 34 and 35, 35 engaging the 5 said screws and serving to clamp the strip 33 in place. It will be observed that the strip 33 provides an electrical connection between the two movable contacts 21, 21, thus, when the movable and fixed contacts are in 10 engagement, completing the circuit through the entire unit.

The electro-responsively controlled means also includes a mechanical connection between the actuator and the contact member, 15 this mechanical connection ordinarily being in the form of toggle links, such as 36 and 37. The two links are pivotally connected together at 38 and are respectively pivotally connected with the actuator and the 20 contact member at 39 and 40. As shown the link 37 is a single link and the link 36 is a double link, preferably formed of a single sheet of metal with the two parts connected by an integral transverse element 41. This 25 element 41 normally engages the link 37 to limit relative movement as clearly shown in Fig. 6. Preferably, a spring 42 is provided which tends to move the two links 36 and 37 into operative aligned position as shown. 30 For limiting movement of the link 36 in the counter-clockwise direction there is provided a pin 43 extending transversely between the side plates 9, 9 and engaging an extension 36^a on the link.

35 Provision is made whereby the electro-thermal strip, upon being heated, serves to change the relationship of the toggle links, so as to break the toggle and permit the contact member to move to its open circuit position 40 entirely independently of the actuator 25. I do not narrowly limit myself as concerns the relationship between the electro-thermal strip and the toggle links, but I have shown a construction wherein the pivot between the 45 contact member and the corresponding toggle link 37 is bodily movable with respect to the said member and wherein the electro-thermal strip serves to relatively move the said pivot and to thereby change the relationship of the 50 links for the purpose set forth. As shown there is provided a strut 44 which is guided for endwise movement relative to the contact member. The thermal strip 33 is curved so as to assume a loop form and it is directly 55 connected with the strut 44 by riveting or otherwise. The other end of the strut serves as the means whereby the corresponding toggle link 37 is pivotally connected with the contact member. As shown the strut 44 is 60 bifurcated at its end and the link 37 is pivoted directly to it. For holding the strut 44 in place and for guiding it so as to permit endwise movement thereof I provide a rod 45 which extends transversely between the 65 two side plates 9, 9 and which is held against

rotation with respect to the said side plates. As illustrated the rod 45 is provided with squared portions at its ends which fit into similarly shaped holes in the side plates. The rod 45 is provided with a guide opening therein through which the said strut 44 extends. 70

Figs. 2 and 6 show the circuit breaker with the several parts in their closed circuit positions, the movable contacts 21, 21 being in engagement with the fixed contacts 15, 15. The circuit is thus established from the terminal 7^a through the cross member 2 and the strap 19 to the right hand contacts 15 and 21. From the right hand contacts the circuit extends through the thermal strip 33 to the left hand contacts and thence through the strap 20 and cross member 3 to the terminal 8^a. The contact member is held in its closed-circuit position as shown by means of the actuator 25 and the toggle links 36 and 37. As clearly shown in Fig. 6 the axis at 38 is above a line connecting the axes 39 and 40, the links 36 and 37 being thus held in their operative positions by reason of the pressure exerted by the 80 springs 24, 24 tending to move the contact member in the counter-clockwise direction. As also clearly shown in Fig. 6 the axis at 39 is below a line connecting the axes 36 and 37, the action of the combined links 36 and 37 85 therefore being to resist the tendency of the actuator to move in the counter-clockwise direction under the influence of the spring 32. 90

Notwithstanding, the tendency of toggle 100 links to hold the actuator in its closed-circuit position as shown in Fig. 6 the said actuator can be easily moved manually to the position shown in Fig. 7 so as to permit the movement of the contact member in the counter-clockwise direction to its open-circuit position. 105 In fact, by means of the toggle links the contact member can be easily moved by the handle in either direction for ordinary switching purposes.

Upon the passage of excess current through 110 the electro-thermal strip 33 there is a tendency for the said strip to straighten out, thus, moving the strut 44 upward as shown in Figs. 2 and 6, the said strut being guided as before stated in the transverse rod 45. Movement 115 of the strut upward serves to move the pivot 40 upward and, inasmuch as the link 36 is held by reason of its engagement with the pin 43, the operative relationship of said links 36 and 37 is broken and the contact member is free to move to its open-circuit position under the influence of the springs 24, 24. It will be understood that this movement to open-circuit position takes place entirely independently of the actuator and will 120 occur even if the actuator is held in its closed-circuit position. Fig. 8 shows the contact member moved to its open-circuit position while the actuator or handle is assumed to be held in its closed-circuit position. If, how- 125

ever, the handle is released or if it is not held at all it immediately moves to its open-circuit position. As soon as it reaches its open-circuit position the toggle links 36 and 37 again assume their normal operative relationship as shown in Fig. 7. When the thermal strip has cooled so as to return the pivotal connection 40 to its normal position the circuit can be again closed by merely 10 moving the handle to its closed-circuit position.

It will be understood that the circuit breaker unit, that is, the side plates 1, 1 and the parts carried thereby may be mounted upon 15 a base 5 such as already described or may be otherwise used, either separately or in combination with other electrical devices. When mounted upon a base such as 5 it may be enclosed in a sheet metal casing such as 46 20 having an opening through which the handle part of the actuator projects. As illustrated the casing 46 is secured to the base 5 by means of screws 47, 47.

What I claim is:

25 1. An automatic circuit breaker comprising in combination, a movable contact member biased for movement towards its open-circuit position, a pair of toggle links adapted when in their operative relationship to 30 hold the contact member in its closed-circuit position, and an electro-responsive means comprising an element inherently responsive to abnormal current conditions in the circuit, the said element being bodily movable with 35 the said contact member and serving upon the passage of excess current through the electro-responsive means to change the relationship of the toggle links so as to release the contact member and permit automatic 40 movement thereof to its open-circuit position.

2. An automatic circuit breaker as set forth in claim 1, wherein the pivot between the contact member and the corresponding 45 toggle link is bodily movable with respect to the said member and wherein the electro-responsive device serves to relatively move the said pivot and to thereby change the relationship of the links for the purpose set 50 forth.

3. An automatic circuit breaker comprising in combination, a movable contact member biased for movement toward its open-circuit position, and an electro-responsively 55 controlled toggle link means normally serving to hold the contact member in its closed-circuit position, the said means including a thermostatic element bodily movable with the said contact member and serving upon 60 the attainment of abnormal current conditions in the circuit to change the toggle link relationship so as to release the contact member and permit automatic movement there- 65 of to its open-circuit position.

65 4. A circuit breaker as set forth in claim

3, wherein the thermostatic element is structurally separate from the toggle links, the said element having one portion thereof rigidly secured to the contact member and having another portion thereof electro-thermally movable and in operative relationship with the toggle links. 70

5. An automatic circuit breaker comprising in combination, a movable contact member biased for movement toward its open circuit position, a pair of toggle links of which one is connected with the contact member, the said links when in their operative relationship serving to hold the contact member in its closed circuit position, and a thermostatic element bodily movable with the said contact member and serving upon the passage of excess current through the circuit to bodily move the pivotal connection between the contact member and the corresponding toggle link so as to change the relationship of the links and thereby release the contact member and permit automatic movement thereof to its open circuit position. 75

6. An automatic circuit breaker as set forth in claim 5, wherein the thermostatic element is a current carrying bi-metallic strip, and wherein there is a strut guided for endwise movement relatively to the contact member, the said strut being connected at one end with the bi-metallic strip so as to be moved thereby and serving at the other end as the means whereby the corresponding toggle link is pivotally connected with the contact member. 90

7. An automatic circuit breaker comprising in combination, a manually operable actuator, a contact member biased for movement independently of the actuator toward its open-circuit position, a pair of toggle links pivotally connected respectively with the actuator and the contact member and serving when in their operative relationship to transmit the motion of the actuator to move 105 the contact member for ordinary switching purposes, and an electro-responsive means comprising an element inherently responsive to abnormal current conditions in the circuit, the said element being bodily movable 110 with the said contact member and serving upon the passage of excess current to change the relationship of the toggle links so as to release the contact member and permit automatic movement thereof to its open-circuit 115 position independently of the actuator.

8. An automatic circuit breaker comprising in combination, a manually operable actuator biased for movement toward its open-circuit position, a contact member biased for 120 movement independently of the actuator toward its open-circuit position, a pair of toggle links pivotally connected respectively with the actuator and the contact member and normally serving when in their operative rela- 125

tionship to hold the contact member in its closed-circuit position and to transmit pressure from the contact member to also hold the actuator in its closed-circuit position, the said links also serving upon manual movement of the actuator to move the contact member for ordinary switching purposes, and an electro-responsive device connected in the circuit and bodily movable with the said contact member, the said device serving upon the passage of excess current to change the relationship of the toggle links so as to release both the actuator and the contact member and permit automatic movement thereof 15 each independently of the other to their open-circuit positions.

9. An automatic circuit breaker comprising in combination, a manually operable actuator, a contact member biased for movement independently of the actuator toward its open-circuit position, a pair of toggle links pivotally connected respectively with the actuator and the contact member and serving when in their operative relationship to transmit the motion of the actuator to move the contact member for ordinary switching purposes, and an electro-thermal strip connected in the circuit with one portion thereof rigidly secured to the contact member and with 20 another portion thereof electro-thermally movable, the said strip serving upon the passage of excess current to change the relationship of the toggle links so as to release the contact member and permit automatic movement thereof to its open-circuit position independently of the actuator.

10. An automatic circuit breaker comprising in combination, a contact member pivotally movable about a fixed axis and biased for movement toward its open-circuit position, a pair of toggle links adapted when in their operative relationship to hold the contact member in its closed-circuit position, and an electro-responsive device connected in the 25 circuit and bodily movable with the said contact member, the said device serving upon the passage of excess current to change the relationship of the toggle links so as to release the contact member and permit automatic pivotal movement thereof to its open-circuit position.

11. An automatic circuit breaker comprising in combination, a manually operable actuator pivotally movable about a fixed axis 30 and biased for movement towards its open-circuit position, a contact member pivotally movable about a separate fixed axis parallel to the first said axis and biased for movement independently of the actuator toward its open-circuit position, a pair of toggle links pivotally connected respectively with the actuator and the contact member and normally serving when in their operative relationship to hold the contact member in its 35 closed-circuit position and to transmit pres-

sure from the contact member to also hold the actuator in its closed-circuit position, the said links also serving upon manual movement of the actuator to move the contact member for ordinary switching purposes, and an electro-thermal strip connected in the circuit and bodily movable with the said contact member, the said device serving upon the passage of excess current to change the relationship of the toggle links so as to release both the 40 actuator and the contact member and permit automatic pivotal movement thereof each independently of the other to their open-circuit positions.

12. An automatic circuit breaker comprising in combination, a manually operable actuator pivotally movable about a fixed axis and biased for movement toward its open-circuit position, a contact member pivotally movable about a fixed axis and biased for movement independently of the actuator toward its open-circuit position, a pair of toggle links pivotally connected respectively with the actuator and the contact member and serving when in their operative relationship to transmit the motion of the actuator to move the contact member for ordinary switching purposes, and an electro-thermal strip connected in the circuit with one portion thereof rigidly secured to the contact member and with another portion thereof electro-thermally movable, the said strip serving upon the passage of excess current to change the relationship of the toggle links so as to release the contact member and permit automatic pivotal movement thereof to its open-circuit position independently of the actuator.

13. A circuit breaker as set forth in claim 12, wherein the pivot between the contact member and the corresponding toggle link is bodily movable with respect to the said member and wherein the electro-thermal strip serves to relatively move the said pivot and to thereby change the relationship of the links for the purpose set forth.

14. An automatic circuit breaker comprising in combination, a manually operable actuator, a contact member pivotally movable about a fixed axis and comprising two parallel side plates spaced apart and perpendicular to the pivotal axis, two fixed electric contacts at opposite sides of the said contact member, two electric contacts carried respectively by the side plates and movable into and out of engagement respectively with the fixed contacts, a pair of toggle links pivotally connected respectively with the actuator and with the contact member between the side plates thereof, the said links serving when in their operative relationship to transmit the motion of the actuator to move the contact member for ordinary switching purposes, and an electro-thermal strip carried by the contact member between the side 120 plates.

plates thereof and electrically connected between the two movable contacts, the said strip serving upon the passage of excess current to change the relationship of the toggle links so as to release the contact member and permit automatic pivotal movement thereof to its open-circuit position independently of the actuator.

15. A circuit breaker as set forth in claim 14, wherein there is a strut mounted between the contact member side plates for movement parallelly therewith, the said strut being connected at one end with the electro-thermal strip so as to be moved thereby serving at the other end as the means whereby the corresponding toggle link is pivotally connected with the contact member.

In testimony whereof I have hereunto set my hand this 21st day of March, 1929.

JOSEPH SACHS.
